(57) **CLAIM**

The ornamental design for a display screen with icon, as shown and described.

DESCRIPTION

FIG. 1 is a front view of a first embodiment of a display screen with icon showing my new design;
FIG. 2 is a front view of a second embodiment of a display screen with icon showing my new design;
FIG. 3 is a front view of a third embodiment of a display screen with icon showing my new design;
FIG. 4 is a front view of a fourth embodiment of a display screen with icon showing my new design;
FIG. 5 is a front view of a fifth embodiment of a display screen with icon showing my new design;
FIG. 6 is a front view of a sixth embodiment of a display screen with icon showing my new design;
FIG. 7 is a front view of a seventh embodiment of a display screen with icon showing my new design;
FIG. 8 is a front view of an eighth embodiment of a display screen with icon showing my new design;
FIG. 9 is a front view of a ninth embodiment of a display screen with icon showing my new design;
FIG. 10 is a front view of a tenth embodiment of a display screen with icon showing my new design;
FIG. 11 is a front view of an eleventh embodiment of a display screen with icon showing my new design;
FIG. 12 is a front view of a twelfth embodiment of a display screen with icon showing my new design;
FIG. 13 is a front view of a thirteenth embodiment of a display screen with icon showing my new design;
FIG. 14 is a front view of a fourteenth embodiment of a display screen with icon showing my new design;
FIG. 15 is a front view of a fifteenth embodiment of a display screen with icon showing my new design;
FIG. 16 is a front view of a sixteenth embodiment of a display screen with icon showing my new design;
FIG. 17 is a front view of a seventeenth embodiment of a display screen with icon showing my new design;
FIG. 18 is a front view of an eighteenth embodiment of a display screen with icon showing my new design;
FIG. 19 is a front view of a nineteenth embodiment of a display screen with icon showing my new design; and,
FIG. 20 is a front view of a twentieth embodiment of a display screen with icon showing my new design.

(Continued)

The broken line shows a display screen and forms no part of the claimed design. The white space between the icon and the broken line forms no part of the claimed design.
